UNITED STATES PATENT OFFICE

WALTER BYRON REMINGTON, OF BIG SPRINGS, NEBRASKA

GUIDING ATTACHMENT FOR TRACTORS

Application filed August 13, 1931. Serial No. 556,915.

This invention relates to an attachment for tractors whereby the machine to which it is connected will be guided properly along a furrow without requiring attention from the

5 driver.

A further object is to provide a guiding attachment which can be applied readily to different makes of tractors.

Another object is to so mount the device 10 as to allow it to be moved quickly into or out of active position.

With the foregoing and other objects in view which will appear as the description 15 proceeds, the invention resides in the combination and arrangement of parts and in the details of construction hereinafter described and claimed, it being understood that changes in the precise embodiment of the invention herein disclosed may be made within the scope 20 of what is claimed, without departing from the spirit of the invention.

In the accompanying drawings the preferred form of the invention has been shown.

25 In said drawings:

Figure 1 is a plan view of a tractor with the guide thereon.

Figure 2 is a side elevation the front axle of the tractor being in section.

Figure 3 is a section on line 3-3, Figure 1.

Figure 4 is an enlarged section on line 30 4-4, Figure 1.

Figure 5 is an enlarged section on line 5-5, Figure 1.

Figure 6 is an enlarged section on line 35 6-6, Figure 1.

Referring to the figures by characters of reference, A designates the front wheels of a tractor adapted to swing about the knuckles B and provided with the usual arms C connected by a rod D.

The axle is engaged by clamps 1 having upwardly extending studs 2 and pivotally mounted on each stud is a lever 3 held in place by a cotter pin 4 or other suitable means.

The rear ends of levers 3 are slotted longitudinally as at 5 to receive studs 6 projecting from blocks 7 having eyes 8 through which rod D is extended. Set screws 9 or the like are used for securing the rod in the eyes and suitable means, such as a washer 10

and cotter pin 11, can be employed for holding each stud against withdrawal from its slot. However the studs can slide freely in the slots.

The forward ends of levers 3 preferably 55 diverge and are provided with openings 12. In one of these openings rotatably seated is the downturned end 13 of a rod 14 and in the other opening is mounted a stem 15 projecting downwardly from an eye 16 mounted on the other end of rod 14. Withdrawal of the parts 13 and 15 from the openings can be prevented by heads 17.

Adjustably mounted on rod 14 rear its ends are collars 18 located close to the outer sides 65 of channeled side members 19. A pipe 20 is rotatably mounted on the rod and the channeled members 19 rest on the ends thereof where they are fastened by clamps 21.

The side members 19 are rigidly connected 70 by cross braces 22 so as to form a frame and seated in notches 23 in the bottoms of the members 19 near their front ends are the ends of an angular tubular bar 24. The bar is secured in these notches by clamp members 25 75 having bar receiving notches 26 and held to the members 19 by bolts 27.

A pair of standards 28 is located beneath bar 24 between members 19 and each has a concavo-convex wheel 29 journaled on a spindle 30 at the lower end of the standard. A head 31 having an angular recess 32 is provided at the upper end of each standard and these heads are held securely to the bar 24 80 by plates 33 and bolts 34. The plates are recessed at 35 so that the bar will rest in the recesses 32 and 25 and thereby hold the standards against rotation about the bar.

The wheels 29 are oppositely disposed and are located where they will travel in a furrow close to and between the hills at the sides thereof.

A bracket 36 is attached to the front of the tractor and can be braced as at 37. A lever 38 95 is pivotally connected thereto and is connected by a link 39 to one of the braces 22. A cable 40 or other connecting means extends from lever 38 to an operating lever 41.

When the tractor moves forwardly between rows being cultivated, the wheels 29 100

will follow the center of the furrow and when they swing laterally the frame formed by members 19 and their connections will shift laterally therewith. Thus levers 3 will be 5 swung on their fulcrums and actuate rod D to turn wheels A and cause the tractor to follow the wheels 29. By actuating lever 41 the wheels 29 can be lifted from engagement with the soil.

10 This device is very simple and inexpensive in construction and is also advantageous because it can be applied readily to tractors of different makes.

What is claimed is:

15 1. A guide attachment for tractors including spaced levers, means for connecting them pivotally to an axle, means for connecting them pivotally to the steering mechanism of a tractor, a frame pivotally connected to both

20 levers for movement therewith, an angular cross bar carried by the frame, standards adjustably connected to the bar, and opposed wheels connected to the standards.

25 3. A guide attachment for tractors including spaced levers, means for connecting them pivotally to an axle, means for connecting them pivotally to the steering mechanism of a tractor, a frame pivotally connected to both levers for movement therewith, an angular

30 cross bar seated in the sides of the frame, means for clamping the bar against said sides, opposed wheels, standards connected thereto, recessed heads on the standards, and means for clamping the bar in the recessed 35 heads.

35 3. A guide attachment for tractors including spaced levers, means for pivotally connecting them to an axle for lateral movement, means for pivotally connecting them to the steering mechanism of a tractor, a rod connecting the levers and movable therewith,

40 a sleeve on the rod, a frame clamped to the sleeve, guide wheels connected to the frame and means for raising and lowering the 45 frame relative to the levers.

In testimony that I claim the foregoing as my own, I have hereto affixed my signature.

50 WALTER BYRON REMINGTON.
